CLAIM

The ornamental design for a protective shield for use
with radioactive materials, substantially as shown.

DESCRIPTION

FIG. 1 is a view in perspective of a protective shield for
use with radioactive materials showing my new design;
FIG. 2 is a side elevational view thereof on an enlarged
scale, the opposite side being the same;
FIG. 3 is a top plan view thereof on an enlarged scale;
FIG. 4 is a rear elevational view thereof on an enlarged
scale;

FIG. 5 is a front elevational view thereof on an enlarged
scale; and

FIG. 6 is a bottom plan view thereof.
